UNITED STATES PATENT OFFICE.

HENRY MILLER, OF SAN FRANCISCO, CALIFORNIA, ASSIGNOR TO AMERICAN CAN COMPANY, OF SAN FRANCISCO, CALIFORNIA, A CORPORATION OF NEW JERSEY.

ATTACHMENT FOR HANDLES.

Application filed November 28, 1922. Serial No. 603,837.

The hereinafter described invention relates to an attachment designed more particularly for the securing of handles to five gallon containers for the holding of oil, gasoline, kerosene, or any other material adapted to be stored within containers and although the invention is more particularly adapted for use in connection with the securing of handles to what is commonly known as five gallon containers, the same is nevertheless equally as well adapted for the securing of handles to metallic bodies generally. The usual method of uniting handles to containers, is to first locate the handle to be secured within a grooved retention plate or clip and then to clinch the clip so as to firmly bind or hold the handle in place within the groove thereof, the clip then being soldered by an operator to the container. Under this method of uniting the handles to the container the entire operation is required to be performed approximately in the factory where the containers are manufactured and inasmuch as the solder for uniting the clip or retaining plate to the container is applied by hand, there is not a uniform distribution of the solder and as a result the fastening plate or clip is not uniformly united to the container or other metallic body to which the handle is attached and it oftentimes happens that in the soldering of the retaining plate or clip to the container top that portions of the said plate or strip do not receive any solder at all, with the result that there is a weak form of union which in many cases is destroyed or ruptured where the filled container is of considerable weight and the handle torn therefrom and the weighted container causes injury by falling onto the foot of the carrier of the package.

The object of the present invention is to provide an attaching means for handles which will permit of the handles being assembled in one plant and distributed to other plants for application to the container or other article to which the handle is to be united and so constructed as to carry fusible means by which the handle on application of heat to said means may be quickly and easily united to the container or article to which the same is to be attached and united thereto by a uniform distribution of the fusible solder relative to the attaching plate or clip.

To comprehend the invention reference

should be had to the accompanying sheet of drawings, wherein—

Figure 1 is a broken end view disclosing a handle united through the medium of the improved attached means to the top end 60 wall of a five gallon container.

Fig. 2 is a detailed perspective view of the handle applied to the retaining means.

Fig. 3 is a bottom plan view of the retaining means for the handle and

Fig. 4 is a bottom plan view of the retaining means with the handle applied thereto.

In the drawings, the numeral 1 is used to indicate an ordinary conventional handle adapted to be secured to the top 2 of an ordinary five gallon container such as is placed on the market for the holding of oil, gasoline and kerosene. The inturned flanged end portions of the handle are adapted to be received into a groove or channel 3 of a fastening plate or handle clip 4, which plate or clip is struck from a single piece of metal and provided with laterally extended flange members 5. In the present case each flange member 5 of the fastening plate or handle clip is formed with two spaced notches 6, which form opposing seats adapted to receive end portions of a wire solder strip 7, the ends of said solder strips being bent or flanged over onto the side wall members of the fastening plate or handle clip 4. In the present case the solder strips, or what shall hereafter be referred to as fusible cleats, are arranged transversely of the fastening plate or handle clip and serve to confine and hold the end portions of the handle within the groove or channel 3 thereof. The handle is thus loosely held within the said channel or groove of the plate handle clip 4, so that the parts thus assembled may be shipped from point to point for uniting to the container or metallic structure to which the handle is to be securely attached. Inasmuch as the fastening plates or handle clips are of uniform size, it is apparent that two strips of fusible cleats of predetermined length are associated with each fastening plate or clip 4, so that with a given number of handle attachments with the handles secured thereto, only a given amount of solder is employed,—as for instance, for each one thousand assembled handles and fastening plates or clips, the maximum amount of solder or fusible material employed is one

pound, where the handle and attaching plate is adapted for use in connection with a five gallon can or container, as against a minimum quantity of three pounds of solder where 5 the handles are united in a manner heretofore employed. While preference is given to the employment of strips or cleats 7 formed from wire solder, it is apparent that ribbon solder may be utilized as the fusible cleats 10 for retaining the handle within the groove or channel 3 of the fastening plate or clip 4 and while preference is given to arranging the fusible cleats 7 transversely relative to the fastening plate or clip 4, it is apparent 15 that the said fusible cleats may be arranged in any other manner relative to the said fastening plate and held thereto by flanging the ends thereof so as to overlie the upper surface of the flange section of the handle retaining clip or attaching plate.

When it is desired to unite or secure the handle to the container or metallic structure to which the same is to be secured, it is only required to properly position the fastening plate or clip 4 relative to a fluxed section of the said container, when on the application of sufficient heat to melt the fusible handle retaining cleat or cleats, the solder will flow evenly and uniformly relative to the under 30 surface of the said retaining clip or attaching member and when cooled or hardened securely hold the same with its held handle 1 to the said container or other metallic structure to which the handle is to be applied. Owing to the uniformity of the flow of the fusible cleats on proper heat being applied thereto, the handle is secured to the container or other receptacle through the medium of the fastening plate or clip 4 without causing a burning of the surface of 40 the member to which the handle is applied and equally so, without causing a smeared and ugly appearance to be given to the surface of the container at the point of union of the attaching strip or cleat thereto and the handle is more firmly united or held to the container than the same is held where the soldering or uniting of the fastening plate or clip to the container is dependent upon 50 the application of solder thereto by an operator.

By the described invention the operation of clinching the handle within the attaching plate or clip is eliminated, inasmuch as the 55 fusible strips of solder serve and answer as cleats for retaining the handle in position relative to the fastening plate or clip 4, and by the use of the present invention there is a saving of not less than one third of the solder heretofore required to unite or attach the handles to the container and the discoloration to the top of the container produced by the means heretofore resorted to for uniting the handles to the containers is 60 entirely eliminated.

An additional important function of the notches in the opposed edges of the clip, aside from holding the ends of the fusible cleats as described, rests in providing means for the ends of the fusible cleats to flow under the flanges of the clip when fusion takes place, and thus utilize all of the fusible cleats for uniting the clips to the container instead of wasting the end portions as would be the case if the fusible cleats were simply 75 bent over the flange edges without the notches. This notched construction results in a considerable saving of solder, of which the fusible cleats are made, as the exact amount of solder necessary for making a 80 properly formed joint is supplied, while without the notches the extreme end portions of each fusible cleat would fuse and lie on the top of the flanges and thus be a total loss 85 because they would not in any manner assist in holding the handle to the container.

While a rectangular shaped fastening plate or clip for the handle provided with a longitudinal extended groove or channel is 90 illustrated in the accompanying drawing, it will be understood that such constitutes merely a preferred form of fastening plate or strip, for the said plate or strip may be circular in cross section or be of any other desired shape, just so long as the same is 95 provided with a grooved or channeled section for the reception of the terminal end portions of the handle 1 to be employed for use in connection with the containers or other structures for which the same is designed for 100 attachment.

Under the present invention the handle, fastening plate or clip, and fusible cleats for the retention of the handle may be assembled in one factory and shipped to other factories 105 or to distant points, there to be united to containers and this shipment made without fear of the handles becoming detached from the securing clip or fastening plate.

The invention fills a long felt want relative to the proper and securely uniting of the handles to containers adapted to receive and hold a quantity of liquid or other materials and where the weight of the filled containers is approximately 100 lbs., serving, as it does 110 to provide a secure union between the fastening plate or clip and the container than has heretofore been produced and providing for the attachment of the handle to the said article without marring or blemishing the 115 surface thereof.

While I have shown and illustrated the invention in its preferred embodiment, I do not wish, however, to be understood as limiting or restricting the invention to the 120 details of construction so shown and described, but on the contrary wish to be understood as claiming the invention as broadly as the state of the art will permit.

Having thus described my invention what 125

I claim as new and desire to secure by Letters Patent, is:—

1. An article of manufacture, comprising a handle of approximately loop formation, a metallic fastening plate provided with a groove therein adapted to receive the terminal end portions of the said handle, said plate having notches formed in opposing edges thereof, and fusible cleats extended transversely of the groove in said plate and having their ends secured in the notched sections thereof for the retention of the handle relative to the groove of the fastening plate, whereby the said handle, fastening plate and fusible cleats when assembled form a portable unit. 5
2. An article of manufacture for the attachment of handles to metallic bodies, the same comprising a fastening plate provided with a groove adapted to receive the terminal ends of a loop handle, said plate having formed in the flanged walls thereof opposing notches or cutouts and a plurality of fusible cleats held to the under surface of said plate by having the end portions thereof extended within the notched sections of the fastening plate and flanged inwardly to overlie a section of upper surface thereof. 20
3. The combination with a sheet metal container, of a handle of approximately loop formation, a metallic fastening plate provided with a channel or groove section for the reception of the terminal end portions of the said loop handle, said fastening plate being provided at opposing edges thereof with notches or cutout sections, and fusible cleats extended transversely of the groove in the fastening plate and having their ends 30
- extended within the notched sections thereof and held to the plate by being flanged inwardly to overlie a portion of the upper surface thereof, said cleats adapted to hold the handle within the groove or channel of the fastening plate and to unite the said plate to the container by a fusion of the fusible cleats held thereto. 40
4. The means for attaching open handles to containers or metallic bodies, the same comprising a fastening plate grooved to receive a portion of the said handle, and said fastening plate being provided with opposing cutouts, fusible means secured to the under surface of the fastening plate and having portions thereof extended through the cutouts of the said plate and flanged to overlie a portion of the upper surface thereof, said fusible means adapted to retain the handle within the groove portion of the fastening plate and permit the attaching of the said plate to a container or metallic body 50
5. An article of manufacture for the attachment of handles to bodies by the application of a fusing heat, consisting of the combination of a clip formed with a channel, a handle having a portion arranged in said channel, and solder crimped to said clip and holding the handle and clip together and adapted when fused to unite said clip with a metallic body, said solder passing across the said channel and the handle portion. 55 60 65 70

In testimony whereof I have signed my name to this specification.

HENRY MILLER.
